Coffee Mill.

Patented Apr. 13, 1836.

4/13/1836 9595X

Charles M. Peckham — New Haven, Connecticut.

Sellers Patent Dated April 13th 1836.

The Schedule referred to in this Sellers Patent and making part of the same, containing a description in the words of the said Charles M. Peckham himself, of his "Improvement in Coffe Mills."

To all to whom these presents shall come: Be it known that I, Charles M. Peckham, of New Haven, in the County of New Haven, in the State of Connecticut, a native citizen of the United States, have invented a new and useful improvement in the construction of Coffe Mills, which I call "Peckham's improved Coffe Mill," and that the following is a full and exact description thereof. My improved Coffe Mill may be made of cast iron, or other suitable metal, & consist principally of the following parts, viz. a Runner, a front & rear shell, an axle or shaft, a regulator, & a wheel or crank. The runner is a flat wheel of hard metal, about three inches ⁱⁿ diameter & three eighths of an inch thick with teeth formed on one side by ledges radiating from the center; Also having teeth on the outer edge or circumference of the runner. At the back of the runner & outside of the teeth is a guard to prevent the teeth of the runner coming in contact with the teeth of the front shell. The front shell covers the runner & has a lip around it as high as the thickness of the runner & is armed with opposing teeth on the inside of the lip corresponding with the teeth on the outer rim of the runner, & also with ledges radiating horizontally from the top, the axle, of the runner as languors & extending to & up the inside of the lip. These radiating ledges on the front shell extend from the mouth of the hopper to the discharging spout & the remaining surface of this shell is depressed as deep as the top of the ledges leaving a smooth surface without ledges excepting a guard ledge to guide the feedings from the hopper in the course of the runner to prevent clogging. To aid the feedings the ledges on the shell form a sort of ramp from the mouth of the hopper gradually diminishing and descending to give a more free entrance thereto. The back shell is similar in shape to the front shell, but is not armed with teeth or ledges. On the corresponding sides of these shells are projections from the hopper to discharging spout when put together, to serve to secure them by screws or rivets, & a iron extends from the back plate or shell to secure the mill in its place. In the center of the shell is a hole to receive the axle of the runner which may be cast iron.

connected with the runner. The axle extending in front is made square at the end to receive the
rein, which is fastened by a nut on the end of the axle. The mill is regulated by a hand
at the back plate, acting against the collet or washer.

(For further illustration of my invention refer to the model & drawings of the same
deposited in the Patent Office.)

I claim as my invention and improvement the peculiar construction of the
grinding surfaces of this mill. I also claim the guard around the mill as above speci-
fied therefore I solicit Letters Patent, according to law.

Dated at New Haven Sept 29th 1836.
